UNITED STATES PATENT OFFICE.

WILLIAM G. CHAPMAN, OF HUNTINGTON, WEST VIRGINIA.

ELECTRICAL PROTECTIVE SYSTEM.

1,223,255.

Specification of Letters Patent. Patented Apr. 17, 1917.

Application filed April 8, 1916. Serial No. 89,879.

To all whom it may concern:

Be it known that I, WILLIAM G. CHAPMAN, a citizen of the United States, residing at Huntington, in the county of Cabell and 5 State of West Virginia, have invented new and useful Improvements in Electrical Protective Systems, of which the following is a specification.

This invention relates to an electrical protective system, the main object of the invention being to provide a system for guarding points or objects to be protected against theft or vandalism and for particularly securing a photograph for purposes of identification of the burglar or would-be thief or 10 vandal, and also for simultaneously giving an alarm.

The primary object of the invention is to provide an electrically controlled photographing apparatus which may be arranged at or near the point or objects to be guarded and protected, and arranged to be automatically operated by an intruder so as to actuate the camera shutter and simultaneously 15 throw into action a flash or other light, and also if desired operate a warning alarm or signal.

A further object of the invention is to provide a protective system of the character described wherein special provision is made 20 for securing a predetermined length of exposure in a simple, reliable and efficient manner.

The invention consists of the features of 25 construction, combination and arrangement of parts herein fully described and claimed, reference being had to the accompanying drawings in which:—

Figure 1 is a sectional side elevation of 30 a photographing camera employed in the system, showing the parts of the system connected therewith.

Fig. 2 is a sectional front elevation of the same.

Fig. 3 is a sectional view of the time limit relay.

Figs. 4 and 5 are plan and sectional views of the platform or primary switch.

Fig. 6 is a diagrammatic view of the system in entirety.

In carrying my invention into practice, I provide a camera 1 having a suitable type of shutter 1^a, shown in the present instance as a swinging dust-proof shutter-cap carried by an elbow-shaped bracket 2. The bracket 2 has one of its arms fixed to the

shutter pivotally mounted upon a fixed support 3^a at the angle of intersection of its arms in proximity to a lever 3 pivoted at one end to the fixed support 3^a. The free 60 end of this lever carries a contact pin, stud or roller 3^b to engage and depress the free arm of the bracket 2. A spring 2^a is fixed at one end to the shutter and at its opposite end to a fixed support. Normally this spring 65 lies on a line in rear of the pivot of the bracket and acts to hold the shutter closed. When, however, the lever 3 is swung downward, the contact 3^b engages and tilts the bracket downwardly and forwardly, the 70 shutter is opened and the spring shifted forward of said pivot line and exerts its contractile energy to quickly open the shutter. The parts above described are preferably 75 enclosed in a dust-proof casing A, and in practice any suitable automatic type of flashlight device (not shown) may be used for producing the required illumination during the exposure period.

The lever 3 is coupled by an actuating 80 connection 4 with the core or cores of one or more solenoids 6 arranged in a normally open camera controlling circuit including a battery or other source of energy B and conductors 7 and 8 leading from the positive 85 and negative poles thereof to switch contacts 9 and 10, upon the closure of which circuit the solenoids will be energized to operate the camera shutter for the photographic action. If desired, an alarm circuit 90 may be arranged to be thrown into action when the camera shutter is operated, which alarm circuit may include a battery or other source of energy B' and conductors 11 and 12 leading from the positive and negative 95 poles thereof to the contacts 9 and 10, within which circuit is disposed a bell or other alarm device 13 which may be arranged at an alarm station or other distant point for notifying a watchman or others of the intrusion. 100

The circuits referred to are controlled by a starting or energizing circuit and a governing circuit between the same and the camera actuating and alarm circuits. The 105 starting or energizing circuit includes a battery or other suitable source of energy B², conductors 14 and 15 and a primary circuit closing device 16. This primary circuit closing device is shown in the present instance in the form of a base plate 17 and a superposed depressible plate or platform 18,

said plates being connected by guide members 19 and normally held spaced by springs 20. Upon the plates are contacts 21 and 22 to which the terminals of the wires 14 and 15 are connected, and which are suitably insulated from each other and normally spaced apart. The circuit closing device may be arranged to be operated in any suitable manner, at a concealed point, as beneath a carpet or rug in proximity to the point or object to be protected, so that when an intruder treads thereon the plate or platform 18 will be depressed against the resistance of the springs and thus bring the contacts into engagement and close the starting or energizing circuit. Also arranged in the starting circuit is what I term a time limit relay 16, the movable core 17' of which carries a piston 18' movable in a dash pot 19', containing a body of oil or other suitable fluid which piston is provided with restricted oil passages 21' and 22', the passage 21' being controlled by a check valve 23. These passages permit of a rapid downward movement of the piston and a slower upward or retarded movement thereof, owing to the fact that on the downward movement of the piston the valve opens under pressure and allows oil to pass upward through both passages, while on the upward movement of the piston the check valve closes and allows the oil to pass only through the restricted uncontrolled passage 22'. Thus provision is made for securing a rapid switch closing movement upon the energization of the relay, and a much slower switch opening movement to maintain the camera shutter open for a predetermined period. The core 17' of the relay solenoid 16' extends loosely through an opening 24 in a pivoted switch member 25, movable downwardly to a closed position by the action of a light or gentle spring 26. The downward movement of this switch is normally arrested by a stop member 27 fixed to the core 17', whereby the spring 26 is normally held tensioned and a contact 28 on the lever maintained out of engagement with a contact 29 on a resilient spring strip 30. Springs 31 connect the solenoid with a fixed support and operate when the solenoid is not energized to hold the core retracted or elevated, with the stop 27 engaging and holding the switch 25 in retracted position, in which the contact 28 lies above and in spaced relation to the contact 29. When the relay magnet is energized the core 17' is drawn downward, thus withdrawing the stop 27 from beneath the switch 25 and allowing the latter to move downward under the action of the spring 26 to circuit closing position, the solenoid continuing to move downward after the switch is closed to bring the stop 27 to a point below the switch and to tension the springs 31, whereby a lost-motion connection between the solenoid core and switch 25

is provided. On the rapid downward movement of the switch the camera shutter mechanism is operated to open the camera shutter and then upon the deenergization of the solenoid magnet the springs 31 operate to draw the core upward slowly against the retarding action of the fluid in the dash pot and until the stop 27 engages and lifts the switch 25 again to open position, against the resistance of the spring 26 which is thereby tensioned, the springs 31 having sufficient energy to overcome the spring 26 and the retarding action of the dash pot fluid in such operation. Hence after the camera shutter has been opened, it will remain open for a definite period to secure a full and complete exposure, irrespective of the amount of time the starting or energizing circuit may be closed, whether momentary or otherwise, so that a positive opening of the camera shutter and maintenance of the same in open position for the period required will be secured.

The switch 25 controls an intermediate circuit in which the above mentioned flashlight or illuminating device may be arranged, and which also serves to control the alarm and shutter governing circuits. This intermediate circuit includes a battery or other suitable source of energy B³, a conductor 32 leading from the positive pole of the battery to the contact strip 30, and a conductor 33 leading from the negative pole of the battery to the switch 25, and arranged in said conductor 33 is a spark coil 34 having spark points 35 and a polarized relay 36, the contact or switch member 37 of which is adapted for coöperation with the contacts 9 and 10 to open and close the camera controlling and alarm circuits. It will thus be understood that when the flashlight or illuminating circuit is closed a spark will be produced across the gap between the points 35 to set off the flashlight device, for the purpose of producing the required illumination, and at the same time the relay 36 will be operated to close the switch member 37, so as to energize the camera shutter controlling and alarm circuits, to effect the opening of the camera shutter through the energization of the magnet 6 and the operation of the alarm 13 at the alarm station or distant point. It will be further understood that these circuits will remain closed until the switch 25 is subsequently opened, irrespective of the time period of the closing of the starting circuit, so that the camera shutter will be positively held open a suitable time to make the exposure. It will be observed that as soon as the connection 4 is drawn downward by the core or cores of the solenoid or solenoids the shutter 1^a will be given an initial opening movement, and this movement will be accelerated and rapidly increased by the action of the spring 2^a, an in-

stantaneous opening action of the shutter being thereby secured. In resetting the apparatus, the shutter cap itself may be closed by hand.

5 In the use of the apparatus for protective purposes in banks, households and other places, the parts of the apparatus will of course be suitably sealed from view and protected against injury, while the camera will 10 be inclosed in a dust-proof casing and arranged so as to be protected from any possibility of damage by the intruder after operation of the apparatus and the general point of location of the camera has been indicated. The essential and primary feature 15 of my invention resides in the provision of an automatic protective system employing a photographic camera which embodies means for absolutely securing a full exposure of the 20 film or plate for the necessary period, whether or not the energizing circuit is but momentarily closed or kept closed for a longer or shorter period by the continued depression of the switch platform. While the 25 described structure is preferred as one means for carrying my invention into practical effect, it is to be understood, the changes in the construction and arrangement of parts may be made within the scope of the claims without departing from the spirit or sacrificing 30 any of the advantages of the invention.

I claim:

1. An apparatus of the character described including a shutter actuating circuit, a sparking circuit, a relay in said sparking circuit and controlling said shutter actuating circuit, a starting circuit, a switch for closing the sparking circuit, and means governed by the starting circuit for instantaneously closing said switch and a suitable time thereafter opening said switch independently of the condition of said starting circuit.

2. An apparatus of the character described including an actuating circuit, a 45 sparking circuit, a relay in said sparking

circuit controlling said actuating circuit, a switch in the sparking circuit, a starting circuit having a circuit closing device, and means controlled by said circuit for instantaneously closing said switch, said switch closing means having means independent of said starting circuit for producing a retarded opening movement of the switch.

3. An apparatus of the character described 50 including an actuating circuit, a lighting circuit, means in said lighting circuit for opening and closing said actuating circuit, a starting circuit having opening and closing means therein, a switch for closing the 55 sparking circuit, an automatically closing switch in the sparking circuit, a solenoid in the starting circuit for normally holding said switch open and permitting closing movement thereof when said solenoid is energized, said solenoid having a spring retracted core and a lost-motion connection with the switch, and a retarding device for controlling the retraction of the core.

4. An apparatus of the character described 60 including an actuating circuit, a 70 sparking circuit, a relay in the sparking circuit controlling the actuating circuit, an automatically closing switch in the sparking circuit, a starting circuit, a solenoid in said 75 circuit having a core slidably connected with the switch and provided with means for normally holding the switch from action, said core having operative movement greater than the extent of closing movement of the 80 switch, spring means tensioned by the operating movement of the core for returning said core and switch to normal position, and a retarding device controlling said core to reduce the speed of retraction thereof.

85 In testimony whereof I affix my signature in presence of two witnesses.

WILLIAM G. CHAPMAN.
